UNITED STATES PATENT OFFICE

100,291

DESIGN FOR A BICYCLE NAME PLATE

Mayo E. Roe, Elyria, and Wilbur Henry Adams,
Cleveland, Ohio, assignors to The Colson Corporation, Elyria, Ohio, a corporation of Ohio

Application April 29, 1936, Serial No. 62,381

Term of patent 7 years

To all whom it may concern:

Be it known that we, Mayo E. Roe and Wilbur Henry Adams, both citizens of the United States, residing at Elyria, in the county of Lorain and State of Ohio, and at Cleveland, in the county of Cuyahoga and State of Ohio, respectively, have invented a new, original, and ornamental Design for Bicycle Name Plates, of which the following is a specification, reference being had to the accompanying drawing forming a part thereof, in which:

Fig. 1 is a side elevational view of a name plate showing our new design;

Fig. 2 is a top plan view of the design shown in Fig. 1;

Fig. 3 is a front elevational view of the design shown in Fig. 1;

Fig. 4 is a sectional view taken on the line 4—4 of Fig. 1.

We claim:

The ornamental design for a bicycle name plate substantially as shown and described.

In testimony whereof, we hereunto affix our signatures this 10th day of April, 1936, and this 27th day of April, 1936, respectively.

MAYO E. ROE.
WILBUR HENRY ADAMS.
